UNITED STATES PATENT OFFICE.

JOHN B. CLERMONT, OF NEW YORK, N. Y., ASSIGNOR TO S AND S WINDOW CORPORATION, OF NEW YORK, N. Y., A CORPORATION OF NEW YORK.

WINDOW.

1,150,929.

Specification of Letters Patent.

Patented Aug. 24, 1915.

Application filed August 31, 1914. Serial No. 859,291.

To all whom it may concern:

Be it known that I, JOHN B. CLERMONT, a citizen of the United States, and resident of the borough and county of the Bronx, city and State of New York, have invented certain new and useful Improvements in Windows, of which the following is a specification.

My invention relates to windows, more particularly of the type known as double-hung windows, in which the sashes under certain conditions are capable of swinging on horizontal pivots relatively to the casing and has for its object to improve the meeting rail construction thereof.

My improvement also contemplates the provision of openings in the upper part of the casing through which access to the usual interior overhead pulleys may readily be had and also includes a readily removable covering means for said openings.

Other objects of my invention will appear from the description hereinafter and the features of novelty will be pointed out in the appended claims.

Reference is to be had to the accompanying drawings illustrating an example of my improvement in which—

Figure 1 is a sectional elevation on the line 30 1—1 of Fig. 2; Fig. 2 is a cross section on the line 2—2 of Fig. 1; and Fig. 3 is an enlarged detail section.

In the drawings 5 represents the window casing having a horizontal partition 6 at its upper portion forming the lower wall or bottom of a chamber 7 in which the pulleys 8 for the accommodation of the sash chains or cords 9 are located. The chains or cords 9 at one end are pivotally secured in pairs at 40 10 to the upper sash 11 and lower sash 12 respectively and at the opposite end are connected with sash weights 13 of any well known description. These sashes under certain conditions are thus capable of a pivotal movement relatively to the casing 5 in vertical planes or about the horizontal pivots 10 and may be normally maintained against such pivotal movement and in the vertical

paths in any suitable or desired manner as for instance by means of movable locking strips 14 and parting strips 15. In the form of window shown and commonly known as a double-hung window the chains or cords for one sash both pass to a sash weight or weights vertically movable at one side of the

casing and the chains or cords for the other sash pass to a weight or weights similarly movable at the opposite side thereof. It is to be understood, however, that my improvements are equally well adapted for use in connection with windows counterbalanced in any other way.

The partition 6 is provided with openings 6^a located in proximity to the pulleys 8 and through which access to said pulleys may be freely had without making it necessary to completely dismantle the window the said openings 6^a being of relatively large dimensions for this purpose. In order that these openings 6^a may normally be closed or covered I provide a cover plate 16 preferably of metal and arranged to extend completely over the lower ends of said openings and preferably secured to and carried by a filler strip 17, the latter being itself removably secured in the casing 5 in any suitable manner as by means of screws 18. The said strip 17, in addition to carrying the cover plate 16 also serves to compensate for the difference in dimensions of the upper and lower sashes necessary to permit the upper sash 11 to be swung on its pivots 10 relatively to the lower sash 12 when this is desired. Thus when the openings 6^a are to be exposed or uncovered, all that is necessary is to lower the upper sash 11 and remove the screw 18 which leaves the filler strip 17 free to be taken out of the casing 5, the cover plate 16 being carried along with said filler strip. When it is again desired to close the said openings 6^a the combined filler strip 17 and cover plate 16 are simply replaced and secured in position without requiring any special manipulation of the cover plate 16 which is returned to and removed from its operative position in the above described way. In its operative position the said cover plate 16 completely seals said openings 6^a against the entrance of dust or other foreign matter and also renders the window fireproof at these points by preventing drafts and the entrance of flames to the chamber 7.

As shown in the illustration the upper sash 11 is provided along its lower edge with a horizontal inwardly extending projection or meeting rail 19, the upper surface of which is formed with a preferably curved or concave groove or recess 20 and an inclined plane portion 21 extending length-

wise thereof. The lower sash 12 is similarly provided along its upper edge with a horizontal outwardly extending projection or meeting rail 22, the lower surface of which 5 is provided with a curved or convex bead 23 and an inclined plane portion 24. The portions 21 and 24 are inclined at the same angle and the concave curve of the groove or recess 20 has a radius corresponding to that 10 of the convex curve of the bead 23, the recess 20 and plane portion 24 extending along the inner portions of the projections 19 and 22 respectively while the plane portion 21 and bead 23 are located respectively along the 15 free edges thereof as is clearly shown in Fig. 2 of the drawings. Thus when the window is completely closed the projection 22 of the lower sash 12 will extend over the projection 19 of the upper sash 11 and the bead 23 will 20 be located in the groove or recess 20 while the inclined plane portions 21 and 24 will be in surface engagement with each other so as to secure a perfect dust and weather-tight joint along the meeting rails of both sashes. 25 It will be seen with this construction that the sashes may be freely moved relatively to each other in a vertical direction and that the meeting rails will become properly re-engaged with each other each time the sashes 30 are brought to their fully raised and lowered positions respectively to close the window. If it is desired to pivotally swing the lower sash 12 relatively to the upper sash 11 when the window is completely closed and the 35 meeting rails 19 and 22 are in engagement with each other it is merely necessary to bring the locking strips 14 or analogous devices to an inoperative position after which the upper edge of the lower sash 12 is sim- 40 ply swung inward away from the lower edge of the upper sash 11. The portions 21 and 24 being inclined downwardly in this general direction will offer no resistance to this actuation of the sash 12 while 45 the bead 23 will readily move out of the recess 20 without moving either the upper or lower sash in a vertical direction to any appreciable extent or without making it necessary first either to lower the 50 upper sash or to raise the lower sash to disconnect the meeting rails as is the case in many existing constructions. The lower sash 12 may be quickly returned to its normal vertical position in the casing in the 55 same way by simply reversing the swinging movement thereof and without necessitating any other actuation of either sash.

My improved arrangement is thus simple in construction and easy to operate and at 60 the same time performs its intended functions with a maximum of efficiency and secured all the advantages of an interlocking

of the meeting rails in the closed position of the sashes without necessitating any extended separate actuation of the two sashes in a 65 vertical direction when a pivotal separation thereof is desired.

It will, of course, be understood that my improved constructions may be readily and satisfactorily combined with windows of a 70 type other than that shown with the same degree of efficiency in operation assured. It will further be apparent that in some cases the bead 23 may be located in the meeting rail 19 and the groove or recess located in 75 the meeting rail 22 or in other words the illustrated position thereof reversed if this should for any reason be found of advantage.

Various changes in the specific form shown and described may be made within 80 the scope of the claims without departing from the spirit of my invention.

I claim:

1. In a window or the like, a casing provided with a chamber at its upper portion 85 and having an opening in the bottom wall thereof whereby access to said chamber may be had, sashes vertically slidable in said casing, sash cord pulleys in said chamber accessible through said opening, a filler piece 90 detachably and rigidly secured to the bottom wall of said chamber and arranged to arrest the upward movement of one sash and means carried by said filler piece and extending over said opening to cover same, said means 95 being arranged to arrest the upward movement of the other sash at a point beyond that at which the upward movement of the first named sash is arrested.

2. In a window or the like, a casing provided with a chamber at its upper portion and having spaced openings in the bottom wall thereof whereby access to said chamber may be had, sashes vertically slidable in said casing, sash cord pulleys in said chamber 105 accessible through said openings, a filler piece depending from said bottom wall and rigidly and detachably secured thereto, said filler piece being arranged to arrest the upward movement of one sash and a plate carried by said filler piece and extending over 110 said openings to cover same, said plate being arranged to arrest the upward movement of the other sash at a point beyond that at which the upward movement of the first 115 sash is arrested.

In testimony whereof I have hereunto set my hand in the presence of two subscribing witnesses.

JOHN B. CLERMONT.
